UNITED STATES PATENT OFFICE.

WILLIAM A. SCHATZ, OF ASTORIA, NEW YORK, ASSIGNOR TO ROTAX CO., INC., OF NEW YORK, N. Y., A CORPORATION OF NEW YORK.

BEVERAGE DISPENSER.

Application filed September 24, 1920. Serial No. 412,510.

To all whom it may concern:

Be it known that I, WILLIAM A. SCHATZ, a citizen of the United States, residing at Astoria, in the county of Queens and State of New York, have invented certain new and useful Improvements in Beverage Dispensers, of which the following is a full, clear, and exact description, such as will enable others skilled in the art to which it appertains to make and use the same.

This invention relates to beverage dispensers and more particularly to beverage dispensers having facilities for cooling and mixing liquids.

It is an object of the invention to provide a beverage dispenser having simple and efficient means for cooling, evenly mixing, and dispensing a plurality of liquids.

It is a further object of the invention to provide such a beverage dispenser comprising features of structural superiority and functional advantage.

Other objects will be in part obvious and in part pointed out hereinafter in connection with the following description of the accompanying drawings, which illustrate a typical embodiment of the invention.

In the drawings,

Fig. 1 is a vertical cross-section of the device;

Fig. 2 is a front elevation of the faucet member;

Fig. 3 is a vertical section of the faucet and adjacent parts; and

Fig. 4 is a fragmentary vertical cross-section of a modified form.

In the preferred embodiment of the invention illustrated, there is provided a container 1, preferably transparent, mounted upon a cooling chamber 2, and communicating with a draw-off faucet 5 by means of a pipe or duct extending through the cooling chamber. A supply pipe 3 conveys water or other liquid under pressure to a coil of pipe 4 within the cooling chamber, also having direct connection to the faucet 5 in which the two liquids are automatically mixed. The chamber 2 may be cooled in any convenient manner as by packing with ice, and a stop-cock (not shown) may be provided preferably above the level of the coiled pipe for draining off water from the cooling chamber. In operation, when the faucet is opened, water under pressure is caused to flow through the coil 4 and

into the faucet, and syrup from the container is also admitted to the faucet. The two liquids are forcibly and thoroughly mixed within the faucet as will be described in detail hereinafter, and the mixture then flows out through the nozzle 7 into a suitable receiver.

The container 1, in the form shown, is provided with an extension or neck 8, which is adapted to be seated in a cup-like part 9 depending from a supporting part 10 of the cooling chamber. A tight joint between the container and its support may be insured by allowing an enlarged portion of the neck 8 to rest on a rubber ring 11 held by the fixed supporting part. A pipe 12 in free communication with the neck 8 of the container is sealed through the bottom of the cup 9 and leads directly to the faucet 5. The container 1 may have an opening at the top for filling and is preferably provided with a cover part 13. As shown clearly in Fig. 1 the neck 8 of the container 1, the cup 9 and the pipe 12 will normally be filled with liquid from the container, thus allowing considerable cooling effect to be realized from the encasing cooling chamber. The liquid in the coil 4 and in the pipe 13 leading therefrom to the faucet will be thoroughly chilled in a similar manner. The walls 14 of the chamber 2 may be packed with any poorly conducting substance, such as fiber, to keep the temperature within the chamber as low as possible.

As shown more in detail in Figs. 2 and 3, the faucet 5 comprises a slightly tapering shell 15 forming a combined mixing chamber and valve within which is attached a tube 16, which may be vertically adjustable so as to transect more or less of the space within said shell. The tube 16 closes the opening at the lower end of the shell 15, but an annular space is left within the shell around the tube further up along its length. The member 15 is seated in a correspondingly tapered supporting part 17 fixed upon the neck 18, through which the pipes 12 and 13 lead to the faucet. The wall 15 is provided with a port 19 registering with the pipes 12 and 13 when the faucet is turned to operative position, as shown in Fig. 3. In this position water under pressure allowed to enter the mixing chamber of the faucet through the pipe 13, is met by the wall of the tube 16, which acts as a sort of baffle, and is forced to

flow around the tube and upwardly in part past the mouth of the pipe 12 before entering the tube through its upper end 20 and being discharged through the nozzle 7. By such a course suction is created at the mouth of the pipe 12 and syrup passes in a steady even flow through this pipe into the mixing chamber. In operative position, the upper end of the tube 16 is preferably on a level with the mouth of the upper supply pipe 12, or above that level, and the discharge opening through the tube is preferably considerably larger than those through the supply pipes, so that there will be no tendency for the liquid to back up through the supply pipe 12, after entering the mixing chamber under pressure through the supply pipe 13. Such a tendency is further counteracted, in the form illustrated, by the pressure already existing at the mouth of pipe 12 due to the head of liquid in the container. The thoroughness of the mixing may be varied to some extent by adjustment of the tubular member 16, so as to vary the capacity of the mixing chamber. It has been found that by the construction described a very thorough and intimate mixing of the liquids is assured. The course of the liquid is altered and in part actually reversed in direction after entering the faucet and by this breaking up of the flow the two liquids are thrown together in such a way as to insure thorough intermingling.

If it is desired to draw off one of the liquids in a clear state, the faucet handle is turned so that a port 21 which registers with but one supply pipe 13 admits but one of the liquids into the faucet. Obviously, the construction may be modified to admit other liquids and allow various combinations thereof. A screw plug 22 may be provided to protect the flow of syrup through the pipe 12 and thus regulate the mixture when a lesser quantity of any particular liquid is desired.

In the closed position as shown in Fig. 1 when the faucet handle is at right angles to the direction of flow of the entering liquids, an imperforate portion of the wall 15 of the faucet closes the mouths of the tubes 12 and 13. When a mixed beverage is desired, a quarter turn of the handle in one direction allows entrance to liquids from both supply pipes and the two liquids are suddenly and forcibly intermingled in the very process of being discharged. From the original closed position a quarter turn of the faucet handle in the reverse direction results in the flow of one liquid clear. Thus substantial and efficient means for accomplishing the objects of the invention are provided and the operation thereof is simple and easy.

A modified form of connection between the bottle and the cooling chamber is illustrated in Fig. 4. In this construction a metal ring 23 is permanently fixed upon a flanged

portion 24 of the neck of the container as shown and is adapted to be attached as by a screw thread connection to a cooperating ring 25 on the supporting member 10. When the parts are assembled the lower edge of the neck 24 is seated on the ring 11, held by the member 25 and the receiving cup 26, and the container is thus tightly but removably secured in position.

As many further changes might be made in the above construction without departing from the spirit and scope of the invention or sacrificing any of its advantages, it is intended that all matter contained in the above description or shown in the accompanying drawings shall be interpreted as illustrative and not in a limiting sense.

It is also to be understood that the language used in the following claims is intended to cover all the generic and specific features of the invention herein described, and all statements of the scope of the invention which, as a matter of language, might be said to fall therebetween.

Having described the invention, what I claim as new and desire to secure by Letters Patent is,

1. In a liquid dispensing apparatus, in combination, a supply source for a liquid under pressure, a container for a second liquid, a mixing chamber closed at one end, conduits leading to said mixing chamber for introduction thereto of said liquids, a tubular member extending within said mixing chamber and forming a baffle disposed so the liquid under pressure is projected from its conduit directly thereagainst, effecting agitation within said chamber resulting in the mixing of said liquids therein, said tubular member providing a discharge opening for the mixed liquids adjacent the upper part of said mixing chamber, and a nozzle communicating directly with said tubular baffle, said tubular member being adjustable to transect a greater or less extent of said mixing chamber so as to vary the extent of mixing within the mixing chamber.

2. In a liquid dispensing apparatus, in combination, a supply source for a liquid under pressure, a container for a second liquid of different consistency, a mixing chamber having a closed bottom, conduits leading to said mixing chamber for introduction thereto of said liquids and having adjacent openings, a baffle in said mixing chamber disposed so the liquid under pressure is projected thereagainst and deflected adjacent the vicinity of the opening for the other liquid, inducing flow therefrom, and effecting agitation within said chamber resulting in the mixing of said liquids therein.

3. In a liquid dispensing apparatus, in combination, a chamber having a discharge opening and a plurality of receiving ports, and a tube in said chamber spaced from said

- ports forming a mixing chamber having a closed bottom and being adapted to divert liquid from one of said ports past another, inducing flow from the latter and effecting mixture of the liquids within said chamber, said tube having an opening to receive liquid from said chamber and to convey it out through said discharge opening.
- 10 4. In a device of the character described, in combination, a chamber having a discharge opening and a plurality of receiving ports and a tube in said chamber spaced from said ports adapted to divert the flow of liquids entering through said ports and adapted to receive liquid from said chamber and to convey it out through said discharge opening, one of said ports lying in the course of flow of the liquid between another 15 of said ports and the receiving end of said tube.
5. In a device of the character described, in combination, a tubular shell forming a wall for a mixing chamber, a discharge 20 nozzle carried by said shell, a plurality of ports adapted to allow entry of liquids into said mixing chamber upon rotation of said shell, said ports being so disposed that the flow of one liquid assists the flow of another 25 into said mixing chamber, means for forcibly mixing said liquids before said liquids enter said discharge nozzle and means for causing discharge of said liquids.
- 30 6. In a liquid dispensing and mixing apparatus, in combination, a faucet comprising a mixing chamber and a discharge nozzle leading therefrom, a supply pipe for liquid under pressure leading to said chamber, a supply pipe for another liquid leading to said chamber, a tubular baffle forming an extension of said nozzle and extending into said mixing chamber adjacent both of the outlets from said pipes, the liquid under pressure being thereby directed from its outlet past the other outlet to effect thorough mixing of the liquids within the chamber.
- 35 7. In a liquid dispensing apparatus, in combination, a tubular shell forming a wall for a mixing chamber and having a plurality of ports therein, a discharge nozzle in communication with said mixing chamber and connected to the lower part of said shell for support thereby, a plurality of conduits leading to said shell and having discharge 40 openings, said shell being movable so its ports register with various combinations of said discharge openings to open the same, or so as to close said openings, and an extension for said discharge nozzle forming a baffle adapted to divert the flow of said liquids within said mixing chamber.
- 45 8. A faucet for dispensing apparatus comprising a rotatably mounted tapering shell circular in cross section and closed at its upper end, said shell having ports through
- its side walls adapted to receive a plurality of liquids, and a cylindrical tube within said shell fitting tightly against the wall of said shell adjacent the lower extremity thereof, said tube extending upwardly within said shell above the level of the ports.
9. A faucet for dispensing apparatus comprising a rotatably mounted tapering shell circular in cross section and closed at its upper end, said shell having ports through 70 its side for a plurality of liquids, and a cylindrical tube within said shell fitting tightly against the wall of said shell adjacent the lower extremity thereof, said tube extending upwardly within said shell and vertically adjustable therein.
10. In a faucet for dispensing apparatus, in combination, a tubular outer shell, a tube within said shell, the wall of which is spaced from the wall of said shell, said shell being movable to admit a plurality of liquids therewithin around said tube and thereby causing discharge of the liquids therethrough.
11. In a device of the character described, in combination, a vertically disposed chamber having a bottom and a discharge opening and a plurality of receiving ports, said receiving ports being in different horizontal planes, said chamber including a rotary hollow valve member having one or more apertures for entry of liquid from said ports, a tube in said valve member spaced from said ports communicating with said discharge opening adapted to divert liquid from one of said ports past another of said ports and having an entry for liquid from said chamber above the bottom of said chamber.
12. In a device of the character described, in combination, a vertically disposed mixing chamber having a bottom and a discharge opening and a plurality of receiving ports, said receiving ports being in different horizontal planes, said chamber including a rotary hollow valve member having one or more apertures for entry of liquid from said ports, a tube in said valve member spaced from said ports communicating with said discharge opening adapted to divert liquid from one of said ports past another of said ports and having an entry for liquid from said chamber above the bottom of said chamber, said tube being vertically adjustable in said valve member to vary the effect of said mixing chamber.
13. In a device of the character described, in combination, a vertically disposed valve seat having a plurality of liquid delivery ports in different horizontal planes, a rotary hollow valve member closed at its upper end having one or more receiving ports adapted to register with one or more of said delivery ports, and a tube projecting into said valve member and spaced from said receiving and said delivery ports to provide an upwardly discharging mixing chamber, said tube

having an entry for liquid from said chamber above the plane of said delivery ports and having an opening for the discharge of liquid from said valve by way of said tube.

14. In a device of the character described, in combination, a vertically disposed valve seat having a plurality of liquid delivery ports in different horizontal planes, a rotary hollow valve member closed at its upper end having one or more receiving ports adapted to register with one or more of said delivery ports, and a vertical tube threaded immediate its ends for support by said valve member and projecting thereinto and spaced from said delivery ports, to provide a mixing chamber, the upper end of said tube being open for reception of liquid from said valve above said delivery ports, said tube providing a passageway for the discharge of liquid from said valve.

15. In a liquid dispensing apparatus, in combination, a supply source for a liquid under pressure, a cooling chamber, a container for a second liquid of different consistency detachably mounted upon said cooling chamber, a mixing chamber, conduits leading to said mixing chamber for introduction thereinto at different pressures of said liquids and having adjacent discharge openings disposed so flow from one conduit passes adjacent to and induces flow from the other and also effects forcible mixing of the liquids within said mixing chamber prior to discharge therefrom.

In testimony whereof I affix my signature, in the presence of two witnesses.

WILLIAM A. SCHATZ.
